UNITED STATES PATENT OFFICE.

WILLIAM J. BREWER, OF BOMBAY, INDIA.

RAILWAY HAND-CAR.

SPECIFICATION forming part of Letters Patent No. 267,772, dated November 21, 1882.

Application filed March 22, 1882. (No model.) Patented in India April 10, 1880, No. 27; in England April 17, 1880, No. 1,588; in Belgium October 18, 1880, No. 52,796; in France October 18, 1880, No. 139,214, and in Austria October 29, 1881, No. 26,478.

To all whom it may concern:

Be it known that I, WILLIAM JOHN BREWER, a subject of the Empress of India, residing at Bombay, India, have invented a new and useful Improvement in Railway Hand-Cars, applicable in part to other vehicles, of which the following is a specification.

This invention is part of my improvements in apparatus for reducing friction of axles, &c., patented in Great Britain by Letters Patent No. 1,588, dated April 17, 1880.

My present invention consists in certain novel combination of parts, hereinafter described and claimed.

15 The object of the first part of this invention is to combine a certain form of anti-friction wheels, hereinafter termed "lever-wheels," with the hind wheels of a hand-car or like track-wheels adapted to rotate independently, so as 20 to avoid grinding or undue strain, and to distribute and equalize wear without complication of parts, which I accomplish by constructing the loose track-wheels with suitable hubs to coact with the lever-wheels, and mounting 25 the lever-wheels loosely on their own axle, which is the load-sustaining axle.

The object of the second part of this invention is to further reduce friction by a compact and simple combination of parts, comprising 30 pedestals and axle-boxes having vertical slots to receive the front axle or a like track-wheel axle, and a lever-wheel axle above it, with lever-wheels mounted in said boxes and forming the upper bearings of said lever-wheel 35 axles, the whole being compactly arranged beneath the car-platform.

The object of the third part of this invention is to combine such lever-wheels with the driving mechanism of the hand-car or like "self-propelling vehicle," and with the track-wheel axle with which said mechanism coacts, in a simple and effective way, which I accomplish 40 by locating all the axes in one and the same vertical plane, and connecting said driving-shaft and track-wheel axle by a driving band and pulleys, so that the tension of said driving-band and the weight of the driving-pulley, as well as the load-strain, are sustained by 45 the lever-wheels, as hereinafter more fully set forth.

Figure 1 of the accompanying drawings represents a vertical longitudinal section of a railway hand-car illustrating this invention; Fig. 2, a vertical transverse section of the same, showing its propelling mechanism in elevation; Fig. 55 3, a detail view of one of the hind wheels and its immediate accessories, partly in section; and Fig. 4 a like view of another wheel, illustrating certain modifications. The planes of the principal sections shown in Figs. 1 and 2 60 are indicated by broken lines correspondingly numbered, and like letters of reference indicate corresponding parts in the several figures.

The said railway hand-car is composed of a platform, A, which may be of customary structure; two pairs of pedestals, B C, bolted to the bottom of said platform near its respective ends, a front axle, D, carrying a pair of track-wheels, w, at its ends, and provided at mid-length with a fast band-pulley, p; a hind axle, E, uniting a 70 pair of loose track-wheels, w²; lever-wheel axles F G, above the respective main axles, provided at their extremities with lever-wheels x x², loose thereon, resting respectively upon the front axle, D, and upon the hubs of the 75 loose hind wheels, w²; a pair of axle-boxes, H, bolted to the front pedestals, B, and provided with lever-wheels x², mounted loosely upon spindle-bolts or pins s and resting upon 80 said lever-wheel axle F; a set of bearing posts 85 or brackets, I J, bolted to the top of the platform A, with their centers in the same vertical transverse plane as those of the front pedestals, B; a driving-shaft, K, provided at mid-length with a driving-pulley, p', and at its respective extremities with hand-crank c, and supported by the upper ends of the higher brackets I; a pair of lever-wheels, x³, arranged 90 between said brackets I and the brackets J, and mounted therein by means of trunnions t, and a driving band or belt, b, connecting said pulleys p' p.

The pedestals B C, axle-boxes H, and brackets I J, have vertical slots to receive the axles D E and F G and the shaft K, so that the only 95 bearings of said axles in the direction of load-bearing strain and of said shaft in the direction of gravitation and principal strain are formed by the peripheries of the said rotary lever-wheels, while said lever-wheels are adapted 100

- by smooth and true bearings to rotate freely, and, serving by the reduction of speed and corresponding increase of power to overcome resistance at their bearings, they form nearly 5 frictionless bearings for the main axles and driving - shaft in the simplest manner. The said adaptation of the main lever-wheels to rotate independently of their rotary axles serves still further to preclude frictional resistance 10 by adapting each wheel to rotate in unison with the coacting axle or hub surface, rotating, if need be, independently, while the rotation of the lever-wheel axles therewith ordinarily distributes and equalizes wear.
- 15 The adaptation of the hind track-wheels to rotate independently is of well-known importance in reducing friction and strain at curves, and the lever-wheels are readily adapted thereto. For this purpose the hub of each loose 15 track-wheel may be extended, as shown in Fig. 3, or the back of the wheel may have an annular recess of sufficient depth to accommodate the coacting lever - wheel within it, as shown in Fig. 4. An advantage of this arrangement 20 is the superior balancing of the load upon the respective wheels, and the lever-wheels may be thus applied to this form of wheel as commonly used on road-engines, such agricultural machines as harvesters, and the like.
- 25 This is illustrated by dotted peripheral spurs in Fig. 4; and this figure also illustrates the employment of lever-wheels having rounded peripheries to preclude unequal strain. Hubs or collars to coact with lever-wheels of this description 30 may be shrunk on or otherwise applied to the rotary axles in line with the respective lever-wheels. Lubricating devices or anti-friction bearings may be used to supplement the lever-wheels, and the details of mechanical construction may be otherwise modified 35 without departing from this invention. The loose wheels may be held in place on the axles in any approved way.
- The entire combination of parts shown in 40 Figs. 1 and 2 may obviously be used in a road-wagon or other four-wheeled vehicle which it may be desirable to propel by manual power, with a simple adaptation of the main wheels to the surface upon which they are to travel, 45 and without any change save the addition of brakes in customary manner. The running-gear is adapted to be attached as a substitute for the ordinary running-gear of street-cars and the like, while different combinations of the 50 same within the scope of this invention may be formed by mounting both axles in either of the two ways illustrated.
- The operation of the several parts is best 55 illustrated by Fig. 1. The driving-shaft K is
- rotated by means of the cranks, c, or either of them, in the direction of the arrow a, and by means of the driving-pulley p', which may be large and heavy, so as to serve as a fly-wheel, transmits motion through the band b and pulley p to the front axle, D, and therethrough to the track-wheels w, as indicated by arrows d 60 and e, propelling the car in the direction of the arrow f. The wheels w turn as indicated by arrow e, by frictional contact with the track, in customary manner, and the axle E ordinarily rotates therewith; but the wheels are adapted to rotate independently and bear their proportion of the load directly. The respective lever-wheels rotate slowly by contact with the surfaces which coact therewith, and operate 65 to reduce friction and distribute and equalize strain and wear, as hereinbefore fully set forth.
- I do not claim broadly the employment or use of what I have termed "lever-wheels" for the aforesaid purposes; but
- I claim as new and of my present invention—
1. The combination, substantially as hereinbefore described, of a pair of track-wheels adapted to rotate independently, and constructed with suitable hubs, and a rotary load-sustaining axle above and parallel with the axle of said track-wheels, having at its respective ends loose lever-wheels coacting with said hubs of the track-wheels, for the purposes set forth.
2. The combination, substantially as hereinbefore described, of the rotary track-wheel axle D, the parallel lever-wheel axle F, provided at its respective ends with lever-wheels x, the pedestals B, and axle-boxes H, having vertical slots to receive said axles, and lever-wheels x', mounted in said boxes and forming the upper bearings of said lever-wheel axle, the axes of all being in one and the same vertical transverse plane, as shown, for the purposes set forth.
3. The combination, in a self-propelling vehicle, substantially as hereinbefore described, of a rotary driving-shaft, K, mounted in vertically-slotted brackets upon the peripheries of a pair of lever-wheels and carrying a driving-pulley, a rotary track-wheel axle in the same vertical plane, mounted in vertically-slotted pedestals beneath and in contact with the peripheries of a pair of lever-wheels and provided at mid-length with a fast pulley, and a driving band or belt connecting said pulleys, for the purposes set forth.
- London, January 23, 1882.
